(57) **CLAIM**

The ornamental design for a display screen with animated graphical user interface, as shown and described.

DESCRIPTION

FIG. 1 is a front view of a first image in a sequence of a display screen with animated graphical user interface, showing our new design;

FIG. 2 is a front view of a second image thereof;

FIG. 3 is a front view of a third image thereof; and,

FIG. 4 is a front view of a fourth image thereof.

The appearance of the animated graphical user interface sequentially transitions between the images shown in FIGS. 1-4. The process or period in which an image transitions to another forms no part of the claimed design.

The broken lines of uneven length show the display screen and form no part of the claimed design. The broken lines of even length illustrate portions of the display screen with animated graphical user interface that form no part of the claimed design.

1 Claim, 4 Drawing Sheets**FIG. 1**

For reference only Notwithstanding anything to the contrary in this application, the claims are directed to all subject matter recited in the following description, including all features and steps which are explicitly recited in the claims. Accordingly, this description is not to be read as a limitation on the scope of the claims. 1. Regorafenib (Regorafenib) is a small molecule angiogenesis inhibitor (SRAF) targeting VEGFR, PDGF and FGFR. 2. Regorafenib (Regorafenib) is a small molecule angiogenesis inhibitor (SRAF) targeting VEGFR, PDGF and FGFR. 3. Regorafenib (Regorafenib) is a small molecule angiogenesis inhibitor (SRAF) targeting VEGFR, PDGF and FGFR.			
And vice versa 1. Regorafenib (Regorafenib) is a small molecule angiogenesis inhibitor (SRAF) targeting VEGFR, PDGF and FGFR. 2. Regorafenib (Regorafenib) is a small molecule angiogenesis inhibitor (SRAF) targeting VEGFR, PDGF and FGFR. 3. Regorafenib (Regorafenib) is a small molecule angiogenesis inhibitor (SRAF) targeting VEGFR, PDGF and FGFR.
